UNITED STATES PATENT OFFICE.

JAMES P. WILLIAMS, OF ST. LOUIS, MISSOURI.

KILN.

1,245,846.

Specification of Letters Patent.

Patented Nov. 6, 1917.

Application filed October 6, 1913. Serial No. 793,743.

To all whom it may concern:

Be it known that I, JAMES P. WILLIAMS, a citizen of the United States, residing at St. Louis, State of Missouri, have invented 5 certain new and useful Improvements in Kilns, of which the following is a specification, reference being had therein to the accompanying drawing.

This invention relates to kilns and more 10 particularly to kilns for burning clay-ware, such as brick and the like.

The primary and basic object of the invention is to provide a continuous gas-fired kiln-structure of such construction and arrangement that a gaseous or liquid fuel may be introduced into the combustion or ware-burning chamber thereof from below the plane of the ware to be treated, and ignition of such fuel be effected and maintained approximately at the floor-line of the structure.

A further object of the invention is to produce a kiln-structure of the kind mentioned which shall be of comparatively inexpensive form but none the less effective 25 for the purposes for which it is designed.

A still further object of the invention is to provide a kiln-structure in which the supply of fuel and withdrawal of gases, etc., are 30 under the control of the attendant and whereby heat may be maintained at any desired degree and uniform, in consequence of which the ware may be uniformly burned and to any predetermined condition.

Another object is to provide such a construction and arrangement of the components thereof that the heat given off by the cooling ware in one section of the kiln may be utilized for drying fresh bricks in 35 another part thereof.

Another object is so to construct and arrange said kiln-components that the heat may be progressively conducted to and into contact with successively-disposed sections 45 of ware in the burning-chamber, whereby each successive section may be subjected to a preliminary heating of a progressively higher degree.

The invention seeks, in general, to provide 50 a kiln-structure which is particularly adapted for burning high-grade ware—though it may be effectually utilized for treating low-grade ware—and which structure, from an operative standpoint, will in practical use

possess a high degree of efficiency and durability and which, structurally considered, will be of the greatest possible simplicity.

Other objects and advantages will be in part obvious from the annexed drawings, and will also be in part pointed out in the following description.

The invention resides broadly in the features of construction, combinations of elements, and arrangements of parts, and in various aggroupments thereof, all as will be exemplified in the structure hereinafter set forth; and, also, in the method of utilizing the components of such structure whereby a gaseous or liquid fuel may be introduced into the combustion chamber of a kiln below the ware therein to be heated and ignition of such fuel be effected and maintained at approximately the floor-line of the chamber; and the scope of application of which will be indicated in the claims hereto appended.

In order that this invention may be clearly comprehended by those skilled in the art, drawings illustrating one of the many possible utilizations thereof are appended hereto as a part of this disclosure; it being manifest that other possible utilizations and embodiments employing the underlying principles of the invention fall within the spirit thereof and also within the objects contemplated thereby.

In these drawings:

Figure 1 is a view in vertical transverse section of a brick-kiln constructed in accordance with my invention;

Fig. 2 is a view in plan of the same, and partly in section;

Fig. 3 is a view in vertical section (on the line 3—3, Fig. 2) of a portion of the kiln, showing on an enlarged scale means for introducing fuel at the floor-level thereof;

Fig. 4 is a view in sectional elevation showing means for controlling the passage of the fuel from the source of supply; and

Fig. 5 is a view in vertical section of the fuel-controlling instrumentalities.

In any embodiment of my invention, it is to be understood that there will, generally speaking, be a main combustion or burning-chamber having one or more slots, orifices or the like in its floor; conduits for conveying the fuel to said slots, etc.; means for controlling the passage of such fuel; and

means for controlling the movement of gases, etc., through the burning-chamber and the withdrawal of such gases from the chamber.

5 This structure is primarily designed for burning appropriate forms of gaseous or liquid fuel, such as vaporized oil, natural, artificial or producer gas. It is to be understood, therefore, that hereafter referring to 10 "fuel," I refer to any of these.

Referring to the drawings, the numeral 1 designates, generally, a housing for the structure. In this instance, I have shown 15 two kiln-components 2 and 3, the former being filled with the ware, ready for burning, and the latter empty, the finished ware having been unloaded from the same.

Each of the kiln-components 2 and 3 is formed with a main burning or combustion-chamber 4 and 5, respectively, in which the 20 ware, such as bricks 7, is housed and treated.

The floor or base-portion of each kiln is provided with a series of juxtaposed openings 8 which may be in the form of short or 25 elongated slots, apertures, or other type of burner orifices, to which fuel of any appropriate form may be conducted, as will be presently explained. These openings will be of such dimensions and form as to permit 30 the ignition of the fuel at or slightly above the upper surface of the floor, the concept of my invention being to effect ignition at the point specified as contradistinguished 35 from known methods of effecting such ignition below or considerably above the floor. By my improvement I am enabled to produce a high degree of heat at the lowest possible point within the burning chamber itself and, thus to secure great efficiency of 40 the heat-units as they rise from the points of ignition. To this end, and as shown in Fig. 1, the ware is so disposed as to form elongated ignition chambers 9 immediately 45 over the openings 8. Any desired number of these ignition chambers may be formed and preferably according to the number of 50 such openings 8. Obviously, however, more than one of such openings may lead into an ignition chamber. The dimensional area of 55 such chambers may be that best suited for the ware being burned or according to its condition when about to be treated.

Extending downwardly from the floor and adjacent to each of said openings is a 55 vertical conduit or flue 10, which, preferably and as shown, is cylindrical in form and communicates with a horizontal passage, conduit, or flue 11. For convenience, I elect to have each conduit 11 supply two of the 60 flues 10. In other words, each conduit 11 is common to two flues 10. As clearly appears in Fig. 2, the conduits 11 underlie the floor and extend laterally of the main chamber 4 and the ignition chambers 9 and, hence 65 for convenience of identification, I shall

herein designate them the "laterals". Where there are six ignition-chambers with a corresponding number of openings or slots 8, there will be a set of three laterals, and these will then, preferably and as shown in 70 Fig. 2, be of relatively different length.

At one end, the laterals are closed, while, at the opposite end, they extend upwardly into a small housing or hood 12 of suitable size and form and preferably constituted of 75 sheet metal because of its characteristic of being light, since they must at times be removed, as presently to be explained.

One of these hoods is disposed in one of a series of doorways 13 and 14 formed at the 80 sides of the kiln-components, and through which (when the hood is removed), the burned or unburned ware is placed in or removed from the main chambers 4 and 5. As shown in Fig. 4, each set of laterals extends into a hood, so that one hood is common to three laterals.

Also communicating with one of these hoods, is an auxiliary fuel-supply passage 15 which, in turn, communicates with a main 90 fuel-supply passage 16 which extends longitudinally of the kiln-structure and connects with a suitable source of supply or generator (not shown). This passage supplies fuel to each and all of the series of hoods 95 which are disposed in the several doorways 13 formed in the kiln-casing.

Obviously, it is desirable to provide means for controlling the passage or flow of the fuel into the different laterals; and, to this 100 end, I have found it convenient to locate such means within the different hoods, and which means may be operated outside thereof. Any suitable type of controlling device 105 may be resorted to, and for illustrative purposes, I have, in Figs. 4 and 5, shown such a device in the form of a flap-valve 17 adapted to close the upper end of the upstanding portion of the lateral, and operated by an actuating rod 18 which extends through the 110 hood whereby it may be manipulated by the attendant. There is one of these valves for each lateral that extends into the hood, and each valve is independently adjustable so that any one or more of the laterals which 115 communicate with the hood may be closed. The valves are suitably pivoted on a hinge-rod 19 carried by the hood and whereby the three valves within the hood may be moved when the hood is. After the hood is removed, the laterals and passage 15 may be closed by plates 20 and 21, respectively, as 120 shown in Fig. 1.

As aforementioned, the hoods 12 are disposed in the doorways 13 and facilitate control of the intake of fuel into the laterals. As usual, the kiln is operated under draft whereby a circulation of the heat-units may be effected and the gases, smoke, etc., withdrawn. For this purpose, the doorways 14— 125

opposite the doorways 18—are provided and in each of these is a removable metallic hood 22—shown on an enlarged scale in Fig. 3. This hood is of such form as to cover an opening 23 formed in a temporary door-section 24 and, also, the upper open end of a conduit or passage 25 which communicates with a main draft passage or flue 26. To close said conduit 25 when the hood 22 is removed, a plate 27 is utilized, as shown in Fig. 1. The flue 26 leads to any suitable draft-producing instrumentality, such as a fan (not shown), or similar device.

The operation of the kiln conforms in general to that of continuous kilns which use a temporary combustible partition. The gas is admitted through the control dampers and laterals, and through the orifices or restricted openings in the floor of the firing-chamber to the combustion-chambers formed from the green ware. Here, the gas is mixed with air and burned.

The air itself is drawn through the firing-chamber by a fan-created draft, and is preferably taken through a chamber in which fired ware is cooling. This serves the double purpose of cooling the burned ware and heating the air to be mixed with the gas.

The products of combustion are in turn carried through chambers in which green ware is stacked for firing. A temporary partition is arranged at the end of a series of these chambers, and the gases are drawn out on the side of this partition adjacent to the chamber being fired. As the fire is advanced, this temporary partition is burned, and the point at which the gases are being removed is correspondingly advanced to the next temporary partition.

When combustion is effected, if it is found that the kiln is heating more rapidly at the top than at the bottom, the draft is increased, and the amount of gas being admitted is cut down. If heat is too great at the floor-level, the draft is cut down to permit the heat to ascend. By this manipulation of the gas-supply and draft, the most delicate control is effected, and this results in a product of uniform color and hardness.

The chambers 4 and 5 are arranged in alinement and there are a plurality of each, communicating at their respective ends and set one back of another, the number depending upon the desired capacity of the plant. They form a continuous tunnel structure of a shape in cross section, similar to that shown in Fig. 1. The continuous firing is effected by working first one and then another of these chambers.

The draft is effected through an exhaust fan at one end, the air being preferably admitted at the other end and through an open chamber or one from which the ware that has already been fired, is being removed.

This air is carried through the next suc-

ceeding chamber which has not been opened, and passing through the ware therein which has already been fired, it takes up heat units from the ware cooling the same and heating the air. The air may in this way be drawn through several of these chambers so that when it is introduced to the chamber in which the ware is about to be fired, it will be at approximately the temperature of this chamber. Here it is mixed with the heating medium which as above described is preferably introduced at or about the floor level.

By applying the draft and admitting air in the manner indicated, it will be seen that the air travels along in a horizontal line through the chambers, the heating medium being admitted from the bottom. This manner of introducing the air and mixing it with the combustible gases at an angle to their introduction, and carrying the draft through the chamber horizontally effects the removal of the heat particles from the roof of the chamber and distributes them more evenly therethrough. It also produces a firing of the ware situated near the floor level due to the fact that the heat which heretofore was in excess at the top of the chamber is by this method presented to the lower portions of the ware.

From the foregoing, it will be perceived that I have succeeded in devising a gas-fired continuous clay-ware burning kiln which is well adapted to achieve the several objects and ends in view. The structure is simple and compact in form and it has a high efficiency.

As many changes can be made in the above construction and many apparently widely different embodiments of this invention can be made without departing from the spirit thereof, it is intended that all matter contained in the foregoing description and shown in the accompanying drawings shall be interpreted as illustrative and not in a limiting sense. It is also to be understood that the language used in the claims is intended to cover all of the generic and specific features of the invention which, as a matter of language, might be said to fall therebetween.

What I claim is:

1. A continuous gas-fired kiln including in combination, a ware-burning chamber, air containing ignition-chambers formed therein, a flooring for said ware-burning chamber provided with openings communicating with said ignition-chambers, a series of laterals communicating with said openings for the passage of fuel only, a gas-supply flue connecting with said laterals, hoods interposed between said laterals and the gas-supply flue, draft-flues communicating with said burning-chamber, and means communicating with said draft-flues for drawing air horizontally through the ware-burn-

ing chamber and thereby maintaining the ignited mixture of gas and air in a condition of incandescence therein.

2. A continuous gas-fired kiln including in combination, a ware-burning chamber, air containing ignition-chambers formed therein, a flooring for said ware-burning chamber provided with openings communicating with said ignition chambers, a series of laterals communicating with said openings for the passage of fuel only, a gas-supply flue connecting with said laterals, hoods interposed between said laterals and the gas-supply flue, gas-controlling dampers in said hoods, draft-flues communicating with said burning chamber, and means communicating with said draft-flues for creating a partial vacuum within the ware-burning chamber and thereby maintaining the ignited mixture of gas and air in a condition of incandescence therein.

3. A continuous gas-fired kiln including in combination, a ware-burning chamber, air-containing ignition-chambers formed therein, a flooring for said ware-burning chambers provided with openings communicating with said ignition chambers, a series of laterals communicating with said openings for the passage of fuel only, a gas-supply flue connecting with said laterals, removable hoods interposed between said laterals and the gas-supply flue, gas-controlling dampers in said hoods, draft-flues communicating with said burning chamber, and means communicating with said draft-flues for creating a partial vacuum within the ware-burning chamber and thereby maintaining the ignited mixture of gas and air in a condition of incandescence therein.

4. A continuous gas-fired kiln including in combination, a kiln-component, a ware-burning chamber therein, doorways leading into said chamber, a flooring for said chamber provided with a series of spaced openings disposed longitudinally of the kiln-component for the passage only of gaseous fuel, a series of lateral-flues each common to a plurality of said openings for conveying the gaseous fuel to said openings, a hood in each doorway common to a plurality of said lateral-flues, a gas-supply conduit leading into said hood, a main gas-supply passage common to all of the laterals, and means communicating with said ware-burning chamber and including a draft-producing instrumentality for creating a partial vacuum above said openings and thereby maintaining the ignited mixture of gas and air in a state of incandescence.

5. A continuous gas-fired kiln including in combination, a kiln-component, a ware-burning chamber therein, doorways leading into said chamber, a flooring for said chamber provided with a series of spaced openings disposed longitudinally of the kiln-

component, for the passage only of a gaseous fuel, a series of lateral-flues each common to a plurality of said openings for conveying the gaseous fuel to said openings, a hood in each doorway common to a plurality of said lateral-flues, a gas-supply conduit leading into said hood, a main gas-supply passage common to all of the laterals, draft-flues leading from the side of the chamber opposite to said gas-supply conduits, and means communicating with said ware-burning chamber and including a draft-producing instrumentality for creating a partial vacuum above said openings and thereby maintaining the ignited mixture of gas and air in a state of incandescence.

6. A continuous gas-fired kiln including in combination, a kiln-component, a ware-burning chamber therein, doorways leading into said chamber, a flooring for said chamber provided with a series of spaced openings disposed longitudinally of the kiln-component for the passage only of a gaseous fuel, a series of lateral-flues each common to a plurality of said openings for conveying the gaseous fuel to said openings, a hood in each doorway common to a plurality of said lateral-flues, gas-controlling devices in said hoods, a gas-supply conduit leading into said hood, a main gas-supply passage common to all of the laterals, and means communicating with said ware-burning chamber and including a draft-producing instrumentality for creating a partial vacuum above said openings and thereby maintaining the ignited mixture of gas and air in a state of incandescence.

7. The method of kiln-burning which consists in arranging within a firing-chamber a combustion-chamber formed from the ware to be fired; introducing fuel to the combustion-chamber through a restricted opening in the floor of the firing-chamber; and effecting a combustion of substantially all the fuel within the combustion-chamber.

8. The method of kiln-burning which consists in arranging within a firing-chamber a combustion-chamber formed from the ware to be fired; introducing fuel to the combustion-chamber through a restricted opening in the floor of the firing-chamber; effecting a combustion of substantially all the fuel within the combustion-chamber; and regulating the heat in the firing-chamber by producing a draft horizontally therethrough.

9. The method of kiln-burning which consists in arranging within a firing-chamber upon the floor thereof, a combustion-chamber of substantial area and formed from the ware to be fired; introducing fuel to the combustion-chamber through a restricted opening in the floor of the firing-chamber; and effecting a combustion of substantially all the fuel within the combustion-chamber and above the floor-level of the firing-chamber.

10. The method of kiln-burning which consists in arranging within a firing-chamber upon the floor thereof, a combustion-chamber of substantial area and formed 5 from the ware to be fired; introducing fuel to the combustion-chamber through a restricted opening in the floor of the firing-chamber; and effecting a combustion of substantially all the fuel within the combustion-chamber and above the floor-level of 10 the firing-chamber and producing a draft horizontally through said firing-chamber.

11. A kiln comprising a tunnel-like ware-burning chamber having a floor provided 15 with a restricted fuel-inlet opening; a combustion-chamber of substantial area formed upon the floor of the firing-chamber from the ware to be fired and communicating with the restricted fuel-inlet opening whereby 20 substantially complete combustion of the fuel may be effected within the combustion-

chamber and above the floor of the firing-chamber.

12. A kiln comprising a tunnel-like ware-burning chamber having a floor provided 25 with a restricted fuel-inlet opening; a combustion chamber of substantial area formed upon the floor of the firing-chamber from the ware to be fired and communicating with the restricted fuel-inlet opening whereby 30 substantially complete combustion of the fuel may be effected within the combustion-chamber and above the floor of the firing-chamber; and means for producing a draft across the firing-chamber horizontally 35 whereby the heat may be regulated therein.

In testimony whereof I affix my signature in presence of two witnesses.

JAMES P. WILLIAMS.
